US00D717677S

(12) **United States Design Patent**
Nardo et al.

(10) **Patent No.:** US D717,677 S
(45) **Date of Patent:** ** Nov. 18, 2014

(54) **METER**

- (71) Applicant: **Hanna Instruments, Inc.**, Woonsocket, RI (US)
- (72) Inventors: **Martino Nardo**, Cumberland, RI (US); **Piero Franco**, Cumberland, RI (US)
- (73) Assignee: **Hanna Instruments, Inc.**, Woonsocket, RI (US)
- (**) Term: **14 Years**
- (21) Appl. No.: **29/449,057**
- (22) Filed: **Mar. 14, 2013**
- (51) LOC (10) Cl. **10-04**
- (52) U.S. Cl. **USPC** **D10/81**

(58) **Field of Classification Search**

USPC .... D14/420, 426-430, 453, 346, 341, 347, D14/412; D13/107, 184; 358/473; 235/462.43, 462.45, 462.47, 462.48, 235/462.44, 462.46, 487, 472.01, 472.02; 16/110.1, 430, 431; 439/133, 135, 482, 439/585, 587, 588, 589; 709/219, 201; 710/73; 320/114, 115, 123; 361/679; 382/313, 321; 455/575.1, 561, 572; D10/81, 46, 78, 104.1, 104; 348/125, 348/E7.085, 82, 65-68, 77, 141, 84, 45, 74; 600/127, 131, 160, 162, 102, 104, 125, 600/109, 177; 601/1; 250/208.1, 330, 250/336.1, 338.1, 339.03, 395, 256; D16/202; 362/1, 109, 294, 373, 399; 713/176; 324/329, 67, 326, 72.5, 110, 324/114, 115, 149, 151 A, 158 F, 156; 73/623, 865.8, 151; 356/246, 241, 237, 356/378; 15/324, 339; 385/116, 117; 29/729, 592.1, 593; D24/107, 186, D24/232, 133, 138; 340/653, 660; 422/63-83, 99, 100, 58, 61, 82.05; 423/43; 436/164, 166, 169, 605; D18/7

(57) **CLAIM**

The ornamental design for a meter, as shown and described.

DESCRIPTION

FIG. 1 is a perspective view of a meter showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

Broken lines and unshaded portions contained within broken lines are not claimed.

1 Claim, 7 Drawing Sheets
